GRINDING APPARATUS

John A. Elmes, Beaver Falls, Pa., assignor to
Walter L. Ryan, Pittsburgh, Pa.

Application November 21, 1945, Serial No. 630,013

2 Claims. (Cl. 51—141)

1

My invention relates to grinding and polishing apparatus and to a method of grinding or polishing articles of various materials, including those of metal, wood, etc.

One object of my invention is to provide apparatus of such form that the surfaces of articles of uneven or non-uniform contours can be efficiently ground and polished throughout all their exposed areas.

Another object of my invention is to provide apparatus of such form that an abrasive belt can readily be caused to present either a convex or a concave surfacing zone for engagement with articles being operated upon.

Still another object of my invention is to provide grinding and polishing apparatus of simple form which can readily be employed in the accurate and expeditious surfacing of curved surfaces of varying radii.

A further object of my invention is to provide an improved method of surfacing articles whereby a single abrasive belt may be employed to rough-grind an article as well as to give a smoother finish thereto.

Some of the forms which my invention may take are shown in the accompanying drawings wherein Figure 1 is a view of a grinding machine in side elevation; Fig. 2 is a fragmentary plan view of the back-up roll of Fig. 1, with a belt and a work piece in operative relation thereto, and Fig. 3 is a side view showing a modification of the machine of Fig. 1.

The apparatus comprises a stand 4 upon which is mounted a motor 5 having a driving pulley 6 for an abrasive belt 7. A stand 8 is provided for idler pulleys 9 and 10 that support and guide the belt 7. A back-up roll 11 is journaled in a bracket 12 that is pivotally supported at 13 upon the stand 8. The bracket has a slot 14 through which a clamping screw 15 extends and has threaded engagement with the stand 8, whereby the bracket 12 can be set at various adjusted positions around its pivot 13. The back-up roll 11 may be of metal and may be faced with rubber or other suitable non-metallic material, when desired.

The pulley 9 is supported by a bracket 16 which is journaled on the frame, on a vertical axis as indicated at 17. An adjusting screw 18 has threaded engagement with a swivel nut 19 that is carried by the stand, and has rotatable connection at 20 with the bracket 16, so that when the handle 21 of the screw 18 is turned, the angular position of the pulley 9 around its pivot 17 will be changed, in order to properly guide the belt 7.

2

The pulley 10 is journaled in a bracket 23 that is pivotally supported at 24, on the stand.

A screw 24 has threaded engagement with a swivel nut 26 that is carried by the stand, and has rotatable engagement with a swiveled pin 27 on the bracket 23. When the handle 28 of the screw is turned, the bracket 23 will be rocked about its pivot 24 to change the tension of the belt 7. A spring 29 interposed between the bracket and a shoulder 30 on the screw serves to prevent chattering of the bracket. It will be understood that the brackets 12, 16 and 23 have bifurcations or arms at the sides of their respective rolls so that both ends of each roll shaft are directly supported.

One important feature of my invention resides in the fact that it is especially adapted for what is called "contour" grinding and polishing, and to this end the peripheral surface of the back-up roll 11 will be of non-cylindrical contour so that it will effectively polish articles of non-uniform contours such as a handle 32 which here constitutes the work piece. The apparatus will be extensively used in polishing other articles such as the outer surfaces of metallic cooking vessels which frequently have considerable curvature in generally axial directions. It will be understood that during surfacing operations, the work piece 32 will be held against the belt 7 with sufficient pressure to deflect the belt to the contour of the roll's peripheral surface.

Abrasive belts that are suitable for this purpose, in that they have sufficient flexibility to permit deflection thereof to the back-up roll contour, without cracking and without spalling off of the abrasive grains, are known in the trade and may suitably comprise a cloth belt to which the grit or abrasive grains are bonded by an adhesive agent.

Another advantage present in my apparatus resides in the adjustable mounting for the back-up roll 11 whereby it can be set at a point where it will deflect the belt to a greater or less degree than shown in Fig. 1, or it can be set back somewhat to a point at which it will not be engaged by the belt until a work piece is pressed against the belt. It will be seen that in the former case, there will be a lesser area of abrasive contact with a work piece, because of the convexity of the belt at the back-up roll; while in the latter case, the belt will be pressed to a concave shape as it passes the back-up, under the pressure of the work piece, and there will be a greater area of contact between the abrasive grains and the work piece.

One of the conditions under which the belt will

be maintained convex at the grinding zone is where greater grinding force is required under a given amount of pressure or where circular articles of small circumference are to be surfaced. With the back-up roll set back sufficiently far, there will be a partial wrapping of the belt about the surface of the work piece with a consequently larger area of the work piece being surfaced at any given instant during rotation of the work piece by the operator. This may be desirable where articles of large circumferences are being surfaced and where not much material is to be ground therefrom.

The apparatus can be used also in the practice of a method whereby a belt having an abrasive of a certain grit size can be used not only for rough or heavy grinding but also to give a smoother finish to an article. The back-up roll can be of cylindrical shape or have its surface contoured as indicated in Fig. 2. It has been found that if the belt has abrasive grains of 60 grit size for example, there will be a markedly different cutting effect on the work piece when applied against the belt at points intermediate the rolls 9 and 11 or the rolls 10 and 11 than when the work piece is applied against the belt directly at the back-up roll. Upon application of the work piece against the belt directly at the front of the backup roll, the grit will give its normal grinding effect. However, when the work piece is applied against the belt at a point where it is not supported by a roll, the grinding action will be less marked. For instance, with a 60-grit belt, the normal 60-grit effect will be produced in a heavy grinding operation against the back-up roll, while when the work piece is moved to a point perhaps mid way between the pulleys 9 and 11, the surfacing will be comparable to that produced by a 120-grit belt, thus, in effect, permitting the grinding and polishing by the use of a single belt.

Referring now to Fig. 3, I show a machine that is similar in most part to the machine of Fig. 1, but in this case, I provide a pair of back-up rolls 34 and 35 which may, as in the case of the back-up roll 11, be of cylindrical contour or have their peripheries of non-cylindrical shape.

The roll 34 is carried by a bracket 36 that is pivotally connected to the stand 8 and is vertically-supported toward its outer end by an adjusting screw 37 which is journaled in a socket 38 that is pivotally connected to the bracket 36 and has threaded engagement with a nut 39 that is rotatably supported in a bracket arm 40, so that when the nut is turned, the roll 34 will be adjusted about its pivot 41 to move it relative to the normal path of travel of the belt 1. The roll 34 is similarly adjusted by a screw 42 and its nut 43.

The rolls 34 and 35 can each be set at a different position of adjustment than the other roll, so that the belt can have different degrees of de-

flexion at the two rolls to better suit grinding operations on articles of different size and shape. For example, articles of one size or shape can be applied against the belt at the roll 34 and articles of other size and shape can be applied against the roll 35. Also, one part of a grinding operation can be performed at the roll 34 and another part of the grinding operation can be performed by pressing the work against the belt at a point mid way between the rolls 34 and 35.

I claim as my invention:

1. The combination with a driving pulley for an abrasive belt and a support for the pulley, of a pulley stand disposed forwardly of the support, pulley-supporting brackets on the stand, respectively at planes above and below the plane of the drive pulley, and projecting forwardly of the stand, guide pulleys on the brackets, in position to receive and guide the abrasive belt, means for adjusting one of the brackets about a vertical axis, to change the angularity of its pulley, means for adjusting the other bracket in a direction to affect the belt tension, a back-up member for the belt, mounted on the stand at a point intermediate the two guide pulleys, and means for adjusting the back-up member relative to the normal path of the belt between the two guide pulleys.

2. The combination with a driving pulley for an abrasive belt and a support for the pulley, of a pulley stand disposed forwardly of the support, pulley-supporting brackets on the stand, respectively at planes above and below the plane of the drive pulley, and projecting forwardly of the stand, guide pulleys on the brackets, in position to receive and guide the abrasive belt, means for adjusting one of the brackets about a vertical axis, to change the angularity of its pulley, means for adjusting the other bracket in a direction to affect the belt tension, a pair of vertically-spaced back-up rolls for the belt, mounted on the stand at points intermediate the two guide pulleys, and means for adjusting the back-up rolls vertically relative to one another and relative to the belt, to control deflection thereof from that portion of its path which is between the two guide pulleys.

Certificate of Correction

Patent No. 2,431,795.

December 2, 1947.

JOHN A. ELMES

It is hereby certified that the name of the assignee in the above numbered patent was erroneously described and specified as "Walter L. Ryan" whereas said name should have been described and specified as *Walter L. Ryman*, as shown by the record of assignments in this Office; and that the said Letters Patent should be read with this correction therein that the same may conform to the record of the case in the Patent Office.

Signed and sealed this 17th day of February, A. D. 1948.

[SEAL]

THOMAS F. MURPHY,
Assistant Commissioner of Patents.
